UNITED STATES PATENT OFFICE.

RALPH M. BUCK, OF RICHFORD, VERMONT, ASSIGNOR TO ATLAS PLYWOOD CORPORATION, OF BOSTON, MASSACHUSETTS, A CORPORATION OF MASSACHUSETTS.

METHOD OF PACKAGING ARTICLES OF FURNITURE AND THE LIKE AND PACK OR SHELL INCASEMENT THEREFOR.

Application filed August 16, 1924. Serial No. 732,459.

This invention relates to the packaging of furniture for shipment, and involves both a novel method of packaging the article of furniture and a novel pack or shell incase-
ment therefor.

For the purposes of this application I shall show and discuss the several steps of a packing operation which may be considered as characteristic and in which the article of furniture to be packed is a vanity case, buffet, chiffonier, or like article, which is usually highly polished on its top, ends and front face, and generally unfinished or only roughly finished on its bottom and back face. Such articles are usually provided with legs or feet, which, while sufficiently strong to support the article, are ill-adapted to stand any racking or strain, especially of a diagonal or lateral character.

Heretofore, in packaging for shipment such an article of furniture, and particularly in packaging such an article for shipment from factory to customer, it has been the practice to wrap the article, in whole or in part, in a protective covering of paper, burlap and excelsior, and to then incase it in the usual slatted packing crate.

Furniture thus crated and shipped is more or less exposed to dirt and cinders and the elements, and consequently almost invariably not only has to be rubbed down and in some instances refinished after reaching its destination, but it can not remain crated for any considerable length of time without having its finish affected by sweating or blooming under the packing. Aside from these objections, the ordinary furniture crate did not properly support and cushion the article of furniture against strains and chafing, and moreover, was relatively expensive, had considerable shipping weight, and required considerable time to properly pack.

To the end therefore of overcoming these objections to existing practice, I have devised my present method of and shell incasement for packaging furniture. In carrying out my invention, I provide a walled shell or bonnet which in characteristic form, suitable for most articles of furniture, consists of a four-sided member having usually an open back adapted to be partially closed by the finished side of the article of furni-

ture incased within said shell and an open front which is subsequently closed by a detachable cover sheet after the article of furniture has been inserted within said shell, the shell itself being, otherwise, so constructed that the article of furniture will be cradled within it by the rigid attachment of one of its unfinished faces to supports embodied in the shell itself, whereby, when assembled, the article of furniture and the shell constitute what may be termed a primary or unitary pack.

In packaging an article of furniture in such a shell and in accordance with my method, I first place the finished front face of the furniture against the flat face of a packing table over which has been laid a protective covering of paper or the like, and wrap this covering about the furniture. I next insert my novel shell incasement over the article from above with the open back of said shell disposed against the packing table, and then screw or otherwise detachably fasten the unfinished face of the furniture to a pair of anchor strips carried by the end walls of the shell adjacent the open bottom thereof. At this state, the position of the furniture is fixed within the shell. I then fasten a transversely disposed cradle strip across the shell in such position as to support the bottom of the furniture and thus cradle the furniture within the shell when the shell is up-ended, after which the shell and attached article of furniture is removed from the packing table, laid front side up on the floor, and a cover sheet detachably fastened over the open front side of the shell.

The method of practicing my invention, together with a characteristic shell incasement in accordance with the principles thereof, and which in itself has been a form found well adapted to practical requirements, is described and illustrated in the accompanying specification and drawings, and the particular features of novelty are pointed out in the appended claims. Throughout the specification and drawings, like reference characters are correspondingly applied, and in the drawings:

Figs. 1 to 4 inclusive are diagrams illustrating the successive steps for the practice

of my method in packaging such an article of furniture as a vanity case,

5 Fig. 1 showing the vanity case laid front side down on the flat top of a packing table with my novel shell incasement disposed thereabove, back side up, in position to be dropped over the vanity case and attached thereto;

10 Fig. 2 showing the shell incasement about the vanity case, said case screwed to and cradled within said shell,

15 Fig. 3 showing the shell and attached vanity case swung off the packing table and disposed on the floor front side up; and

Fig. 4 showing the front closure in position to be attached over the open front side of the shell.

Fig. 5 is a section on the line 5—5 of Fig. 4.

20 Fig. 6 is a skeletonized view particularly showing the cradle strips of the shell incasement, and

Figs. 7 and 8 are sections on the lines 7—7 and 8—8, respectively of Fig. 2.

25 Before proceeding to a description of my novel method, I shall first describe the construction of a preferred shell incasement which I use to carry out my method. This shell consists of a four sided member comprising a solid top wall 1, solid end walls 2 and 3, and a bottom wall 4, which is preferably of slatted type. The solid top and end walls are preferably of veneer or the like. All walls are suitably tied together by appropriate frame strips 2' and cross-braced as indicated at 3' in Figs. 1 and 2, and these strips and braces may be of scrap lumber.

30 The walls 1, 2, 3 and 4 therefore define a generally rectangular shell closed at top, bottom and ends, but initially open from front to rear. For convenience of identification, the open front is designated by the numeral 5 and the open back by the numeral 6. While these sides 5 and 6 are not necessarily entirely open, I shall refer to them particularly as open sides in contradistinction to the walls 1, 2 and 3 which are wholly closed, and preferably tightly closed, so as to afford full protection to the finished surfaces of the article of furniture which is to be enclosed within the shell.

35 Extending from top to bottom of the shell along its open back face 6 is a pair of longitudinal hanger bars 7 which are nailed or otherwise permanently fastened to the adjacent edges of the end walls 2 and 3 of the shell. These hanger bars 7 overlie the edges of the unfinished or roughly finished back of the article of furniture F to be packaged when the shell is applied over the furniture as shown in Fig. 2, and they and the article of furniture are adapted to be engaged by suitable detachable fastenings, shown as screws 8 in Fig. 2, which rigidly draw the 40 article of furniture up against said bars

whereby the shell and article of furniture are firmly held together against relative movement and constitute a unitary pack.

45 One or more transverse cradle strips 9 (Fig. 6) are then permanently fastened 70 across the shell between its top and bottom and closely adjacent the bottom wall of the article of furniture so as to cradle the furniture within the shell. These strips 9 at their ends rest on cleats 10 nailed to the 75 end walls 2 and 3 of the shell. The cradle thus constructed is so disposed as to bring the legs f of the article of furniture slightly clear of the bottom wall 4 of the shell.

Finally the open front of the shell is 80 closed by a solid sheet of veneer or the like 11 (Fig. 4), which with the solid veneer walls 1, 2 and 3 completely closes the shell on four sides.

Having thus described the construction of 85 my novel shell incasement, I shall now proceed to a description of my novel method of packaging.

90 In packaging an article of furniture in accordance with my method, I first cover the face of a flat topped packing table T with a sheet of wrapping paper P and lay on this protective sheet a pair of padded spacer bars B on which the article of furniture F to be packed is laid with its finished front disposed against the paper sheet and its unfinished back uppermost, as shown in Fig. 1. The edges of the paper sheet are then folded around the article of furniture and if desired may be lightly tacked to it.

95 The next step in my method consists in laying my novel shell incasement from above over the article of furniture thus positioned on the packing table. This step is illustrated diagrammatically in Figs. 1 and 2. 105 Fig. 1 shows the shell as about to be placed over the article of furniture resting on the packing table, and Fig. 2 shows the shell as having been dropped down on to the packing table to enclose all four sides of the article of furniture, after which shell and article are firmly but detachably fastened to each other to prevent relative displacement thereof.

110 This may be conveniently accomplished 115 by screwing the shell directly to the unfinished back of the article of furniture, and I have so shown it in Fig. 2, wherein the vertical hanger bars 7 at the corners of the open back of the shell are shown as screwed at 8 120 to the article of furniture. These screws 8 are, of course, withdrawn when the article of furniture is unpacked.

125 The piece of furniture is now firmly but detachably fixed in its proper positional relationship within the shell, but in order to avoid placing the full carrying strains of the furniture on the screws 8, I next construct the cradle 9 which carries the full 130 weight of the article of furniture when the

shell is up-ended and ready for shipment. This cradle lies directly under the bottom wall of the article of furniture and thus supports the weight of the furniture when the shell is up-ended.

The article of furniture is now rigidly hung within the shell with the unfinished back of the article of furniture partially closing the open back of the shell (see Figs. 7 and 8). At this stage of my method, the shell is ready to be closed across its open front towards which the finished face of the article of furniture is disposed.

The next step in my method therefore consists in removing the shell and attached article of furniture from the packing table and closing it across its open front face. This may be conveniently accomplished by simply swinging the shell over upon itself from the packing table onto the floor, as diagrammatically illustrated in Fig. 3, so as to present the uncovered front face of the shell upwardly in position to receive the front closure or cover 11 which is preferably a solid sheet of veneer or the like of the proper dimensions to completely close said open front and adapted to be tacked or otherwise secured thereover.

The article of furniture is now completely incased and rigidly but removably secured in its incasement. In this condition it is ready for shipment, although in the case of articles of furniture of unusual size or weight it is sometimes desirable to brace them across the partially opened back of the shell and this may be conveniently done by simply nailing one or more brace strips across the back of the shell.

By making the front 5 as an open front which is subsequently closed by the cover sheet 11 after the furniture has been cradled within the shell, the operation of packaging the article of furniture is not only greatly facilitated but the furniture itself may be definitely and firmly attached to and cradled within the shell in its proper positional relationship, without the necessity of elaborate wrappings and without danger of strain or chafing in shipment. The shell is a closely fitting conformed incasement within which the article of furniture is fixed and supported in such relation that there is no appreciable physical contact between shell and furniture. Hence, furniture so packaged has been found to have a high increased average improvement in condition and can be packed and unpacked with greater ease and rapidity than under existing methods.

Although I have shown and described my invention in its adaptation to the packaging of furniture, it is to be understood that such treatment is purely illustrative and in no way limiting, and that various other articles may be packaged and shipped with corresponding advantage. Similarly, of course,

various modifications in design and structure of the shell itself may be made, for different styles and articles of furniture. These, and such other variations and departures as fall within the purview of my invention may all be resorted to within the limits of the appended claims.

What I therefore claim and desire to secure by Letters Patent is:

1. A shipping pack for an article having a plurality of finished faces and at least one unfinished face, comprising a shell enclosing corresponding finished faces of the article and open from front to rear, means carried by and adjacent the open back of said shell and attached to and supporting the article within the shell with its unfinished face disposed towards the open rear of the shell, and constituting a partial rear closure of said shell, and a front closure adapted to be removably fastened over the open front of said shell.

2. A shipping pack for an article having a plurality of finished faces and at least one unfinished face comprising a shell enclosing corresponding finished faces of the article and open from front to rear, means carried by and adjacent the open back of the shell and attached to and rigidly supporting the article within said shell in spaced relation from the walls thereof with its unfinished face disposed towards the open rear of the shell, said unfinished face constituting a partial rear closure of the shell, and a front closure adapted to be removably fastened over the open front of said shell in spaced relation from the contained article.

3. A shipping pack for an article having a plurality of finished faces and at least one unfinished face comprising a shell enclosing corresponding finished faces of the article and open from front to rear, a pair of longitudinally disposed hanger bars extending along the open back of said shell adjacent its end walls, means for detachably fastening the unfinished face of the article to said hanger bars whereby all of the finished faces of the article are maintained in spaced relation from the shell, said unfinished face of the article constituting a partial rear closure of the shell, and a front closure adapted to be removably fastened over the open front of said shell in spaced relation from the contained article.

4. A shipping pack for an article having a plurality of finished faces and at least one unfinished face, comprising a shell enclosing corresponding finished faces of the article and open from front to rear, a pair of longitudinally disposed hanger bars extending along the open back of said shell adjacent its end walls, means for attaching the unfinished face of the article to said hanger bars, said unfinished face and said hanger bars constituting a partial rear closure of

the shell, and a front closure adapted to be removably fastened over the open front of said shell.

5. A shipping pack for an article having a plurality of finished faces and at least one unfinished face comprising a shell enclosing corresponding finished faces of the article and open from front to rear, means carried by and adjacent the open back of said shell and attached to and supporting an article within the shell with its unfinished face disposed towards the open rear of the shell, a transversely disposed cradle supported within said shell intermediate of its top and bottom walls and designed to support the article to be packaged from below, said unfinished face of the article constituting a partial rear closure of the shell, and a front closure adapted to be removably fastened over the open front of said shell.

6. A shipping pack for an article having a plurality of finished faces and at least one

unfinished face, comprising a shell enclosing corresponding finished faces of the article and open from front to rear, a pair of longitudinally disposed hanger bars extending along the open back of said shell and adapted partially to close said open back, means for detachably fastening the unfinished face of the article to said hanger bars whereby all of the finished faces of the article are maintained in spaced relation from the shell, a transversely disposed cradle supported within said shell intermediate of its top and bottom walls and designed to support the article to be packaged from below, said unfinished face of the article with said hanger bars constituting a partial rear closure of the shell, and a front closure adapted to be removably fastened over the open front of said shell in spaced relation from the contained article.

In testimony whereof I affix my signature.

RALPH M. BUCK.
